UNITED STATES PATENT OFFICE.

ANDREW FLOHR, OF SACRAMENTO, CALIFORNIA.

BEAN-CUTTER.

SPECIFICATION forming part of Letters Patent No. 239,235, dated March 22, 1881.

Application filed October 16, 1880. (Model.)

To all whom it may concern:

Be it known that I, ANDREW FLOHR, of Sacramento, in the county of Sacramento and State of California, have invented a new and valuable Improvement in Bean-Cutters; and I do hereby declare that the following is a full, clear, and exact description of the construction and operation of the same, reference being had to the annexed drawings, making a part of this specification, and to the letters and figures of reference marked thereon.

Figure 1 of the drawings is a perspective view. Fig. 2 is a horizontal section. Fig. 3 is a vertical cross-section.

This invention relates to devices for cutting beans; and it consists in the construction hereinafter specified.

In the annexed drawings, A represents a frame having cheek-pieces B B, hopper C, lower opening, D, and clamps E F. Held within the frame and between the cheek-pieces are two rollers, G H. Roller G consists of a shaft, g, having collar n, screw-stem p, and nut r, between said collar and nut being clamped the cutting-disks b, and intervening collars, a. Upon one end of shaft g is the handle I. Roller H is hung on a line with the rotary cutter G, and has in its periphery grooves g', opposite to and adapted to receive the cutting-edges of cutters or disks b. Roller H is preferably made partially hollow, and is hung on shaft h, whose ends pass through slots e in cheek-pieces B B, and are journaled in plates K K, which are adjustable along said slots e by means of pins k and slots k', by which construction the device can be regulated to cut different sizes.

Fastened to one side of opening D is a clearer,

L, between whose teeth l the cutters b pass, and are thereby cleared and kept from being fouled.

In this device the cutting-roller G forms the knife, and roller H the cutting-block, between which the beans fed in at the hopper are readily chopped or cut. As the rotary cutter revolves, the edges of its disks bear into grooves in the cutting-block, and by friction cause the cutting-block to revolve in an opposite direction, whereby the cut beans are carried down between the disks and fall through opening D.

I am aware of Patent No. 106,520, which shows a cutter similar to mine.

My device is made adjustable, as shown and described, so that it can be used for beans of various sizes, and also for a variety of vegetables, it only being necessary to change the relation of the cutter and the block.

What I claim is—

Rollers C and H, arranged in line, in combination with frame A, having slots e in its cheek-pieces B B, plates K, having slots k', journals h, passing through slots e and having bearings in plates K, and pins k, passing through slots k' and entering cheek-pieces B B, whereby the plates K can be moved along said cheek-pieces and the position of the rollers with relation to each other be changed.

In testimony that I claim the above I have hereunto subscribed my name in the presence of two witnesses.

ANDREW FLOHR.
